UNITED STATES PATENT OFFICE

HENRY G. WOEHLER, OF ST. LOUIS, MISSOURI, ASSIGNOR TO NIEDRINGHAUS, INC., OF ST. LOUIS, MISSOURI, A CORPORATION OF MISSOURI

REENFORCING MEANS FOR METALLIC DOORS

Application filed November 23, 1928. Serial No. 321,301.

My invention relates to reenforcing means for metallic doors, and, more particularly to metal doors of the type disclosed in my co-pending application, Serial Number 259,192, 5 wherein opposite sides of the door are formed from single and like sheets, or plates of metallic stock in such a manner as to integrally form the opposite sides of the panel, the opposite sides of the molding, the opposite sides 10 of the stiles and the opposite sides of the cross-rails, although not necessarily limited thereto.

A further object of the invention is to eliminate the necessity of rivets, or similar fastening means in securing the reenforcing means to the cross-rail and stile sections of the door plates, by suitably welding two members of the reenforcing means to opposite plates of the door prior to assembling the 20 door proper.

A further and essential object of the invention is to provide a door of the above character with reenforcing means disposed between the stile and cross-rail sections of 25 the door adjacent the integral juncture of the stiles and cross-rails with the molding so as to maintain a uniform gauge or thickness for the stile and cross-rail sections of the door throughout the distance from their outer to 30 their inner edges.

A still further object of the invention is the provision of reenforcing means for metallic doors which possess advantages in points of simplicity and efficiency, and, at the same 35 time proves itself comparatively inexpensive in cost of manufacture.

With the above and other objects in view, the invention consists in the novel features of construction, arrangement and combination 40 of parts hereinafter more fully described and finally pointed out in the claims hereto appended.

Referring to the accompanying drawings 45 forming a part of this specification, wherein like characters of reference denote similar parts throughout the several views:

Fig. 1, is a perspective view showing my improved door.

Fig. 2, is an enlarged vertical sectional

view through the door, taken on line 2—2 of Fig. 1.

Fig. 3, is a detail in perspective of one corner of the door.

Fig. 4, is a detail in sectional elevation 55 showing the extended ends of the key member of the reenforcing means located between one of the cross-rail sections of the door as bent over to engage the key members of the reenforcing means between the stile sections 60 of the door.

Fig. 5, is a detail in perspective of a portion 65 of one of the bracing tongue members of the reenforcing means of which there are two alike.

Fig. 6, is a detail in perspective of the locking member of the reenforcing means.

In the drawings, I have shown a metallic door comprising the metallic facing member 1, the panels 2, the molding 3, the stiles 4 and the cross-rails 5. The door is formed from two sheet metal plates 6 secured to a suitable facing or edging member 1 along the stiles and cross-rails thereof, by a welding process, as indicated by the welds 7. The opposite sides of the door including the molding are made up of single sheets of metallic material similarly shaped as shown in Figs. 1 and 2. It will be noted that the molding 4 is integral 70 with the panel, stiles and cross-rails and formed by means of a drawing or stamping operation, as distinguished from a bending operation and that the corners designated 75 8 of the molding 4 are curved, as distinguished from a beveled corner.

A door such as above described and disclosed in my above referred to co-pending application, is not sufficiently interiorly strengthened to positively prevent variations 80 in gauge or thickness of the stile and cross-rail sections at their inner edges adjacent the outer edge of the integral molding relative to the outer edges thereof, or at intermediate points due to the fact that each door plate is formed from a single sheet of metal by a 85 stamping or drawing operation.

In order to further secure and maintain a uniform and even gauge, or thickness through the stile and cross-rail sections of the door, I provide transversely disposed reenforcing 90 100

or bracing means for each stile and cross-rail section of the door. Each reenforcing, or bracing means comprises a pair of like metallic bracing members 9 and each bracing member is provided with a base or foot 10 at their outer edges and they are disposed at a right angle to the like bracing members 9. The inner edge of each bracing member 9 is folded over, as at 11, to provide the flanges 12 and the channels 13 between the flanges and their respective bracing members. A metallic key member, or keeper 14 made from a single strip of metal, is so shaped by folding its edge portions under as to provide a pair of flanges 15, the channels 16 and a gap 17 between the ends of the flanges 15. The key member 14 is adapted to be slidably mounted upon the bracing members 9 with the flanges 12 of the bracing members receivable in the channels 16 of the key member 14, and the flanges 15 of the key member 14 receivable in the channels 13 of the bracing members. The folded ends 11 of the bracing members are preferably in contact with each other and receivable in the gap 17 of the key member for establishing a frictional interlocking connection between the bracing members and the key member to prevent spreading, or contracting of the bracing members when so interlocked, thus preventing variations in thickness of the cross-rail and stile sections of the door at their inner edges relative to their outer edges, as is manifest.

In practice, there is a bracing member 9 secured to each stile section 4 and to each cross-rail section 5 of each door plate 6, before the two door plates have been welded to the facing or edging member 1 and before the key member 14 has been applied to the bracing members 9. The key members 14 are applied to the bracing members 9 before the plates 6 are welded to the facing member 1. The key members 14 which co-act with the bracing members 9 secured to the cross-rail sections 5 are preferably, although not necessarily, each provided with the flat end extensions 18 which are adapted to be bent over for contact with the key members 14, which connect the bracing members 9 that are secured to the stile sections 4 of the door to prevent possible longitudinal movement of any of the four key members employed hence eliminating the possibility of any rattle developing within the door by the shifting of the key members 14 upon the respective bracing members. The location of each bracing member 9 is at, or adjacent the junction of the inner edges of the stile sections and cross-rail sections with the outer edges of the integral molding section 3. The base portion 10 of each bracing member 9 is secured to the inner face of its respective door plate 6 by a suitable welding operation such for instance as indicated by the spot welds 19, but it is evident that the

bracing members 9 may be secured to the one piece door plates 6 by roll welding.

When it is desired to assemble the door the one piece door plates 6 are first connected by applying a keeper 14 to each pair of bracing members 9, of which there are a pair for each stile and each cross-rail of the door. The door plates 6 having been thus first connected, the stile and rail sections of each door plate can be then welded to the facing or edging member 1.

It will be apparent from the foregoing description that I provide a cheap and simple internal reenforcement for the inner edges of the stiles and cross-rails to prevent bulging or sinking of the stiles and cross-rails adjacent the outer edge of the molding formed integral with the stiles, cross-rails and the panel of the door, which were it not for the reenforcing means, would not have any internal bracing support at the inner edges of the stiles and cross-rails of the door due to the fact that the panel, molding, stiles and cross-rails are integral, the parts being integrally formed from a single sheet of metal by a drawing or stamping operation, as distinguished from a bending.

While the door stile and cross-rail reenforcing means above described could be used in metallic door structures, stiles and cross-rails are formed independent of each other as well as independent of the panel, and in door structures where the panel, stiles and cross-rails are formed from single sheets, with the cross-rails split at their juncture with the stiles, it is especially applicable to a three piece metal door structure, wherein the panel section, molding section, stile sections and cross-rails sections are all formed from a single stamping without any seam appearing between the cross-rail sections and the stile sections and without any seam appearing between the panel sections and molding sections and the stile and cross-rail sections.

The many advantages of the herein described invention will readily suggest themselves to those skilled in the art to which it appertains.

From the foregoing description, it is evident that a simple device for this purpose has been disclosed, but it is to be understood that I do not desire to restrict, or limit myself to the very details of the construction shown and described, which is merely illustrative, it being obvious that changes, not involving the exercise of invention, may be made without conflicting or departing from the spirit of the invention within the scope of the appended claims.

What I claim is:

1. In combination with an all metal door embodying a channel edge facing member and side plates wherein the stiles, the cross rails, moulding and panels are integrally

formed, of reinforcing means disposed between the side plates of the door and embodying a pair of angle bars securely fixed to the inner face of each side plate adjacent to the outer edge of the moulding thereof, one arm of each angle bar having its side edge folded over and adapted to contact with its mate midway the space between the side plates of the door, a slideable metallic lock strip having folded side edges adapted to interlock with the folded side edges of the opposed angle bars for uniting them to prevent separation of the angle bars relative to each other and a tongue directed from each end of the locking strip adapted to be bent at a right angle to the locking strip to arrest longitudinal displacement of the locking strip mounted upon the folded side edges of the angle bars.

20 2. Internal bracing for the cross-rail and stile sections of metal side plates for all metal doors adjacent mouldings integral with the cross-rails and stile sections comprising an angle bar secured to the inner face of the 25 stile sections of each side plate, one arm of each angle bar being folded along its side edge and adapted to contact with its mate midway the space between the two side plates of the door, a metallic lock strip having folded 30 over edges adapted for interlocking engagement with folded side edges of the opposed angle bars, an angle bar secured to the inner face of the upper and lower cross-rail of each side plate, one arm of each angle bar being 35 folded along its side edge and adapted to contact with its mate, a metallic locking strip having folded over side edges adapted for interlocking engagement with the folded side edges of the opposed angle bars and 40 tongues directed from the ends of the latter locking strips, said tongues adapted to be bent into engagement with the first mentioned locking strips to prevent longitudinal displacement of all the locking strips upon the 45 folded side edges of their respective angle bars.

In testimony whereof, I have hereunto affixed my signature.

HENRY G. WOELHLER.
